CIRCUIT BREAKER

Hiller D. Dorfman, Forest Hills, Pa., assignor to
Westinghouse Electric & Manufacturing Company, East Pittsburgh, Pa., a corporation of Pennsylvania

Application March 25, 1938, Serial No. 198,076

14 Claims. (Cl. 200—88)

The invention relates to circuit breakers, in general, and more particularly to circuit breakers of the type in which the breaker operating means is manually operable to open and close the circuit, and is automatically operable to open the circuit in response to overload or short circuit conditions.

An object of the invention is the provision of a circuit breaker embodying an improved trip mechanism that is operable to effect opening of the breaker after a predetermined time interval in response to lower magnitude overloads in the controlled circuit, and operable to effect opening of the breaker immediately upon the occurrence of higher magnitude overloads or short circuit conditions in the controlled circuit.

Another object of the invention is the provision of a circuit breaker with an improved trip device embodying a thermally responsive trip element and an electromagnetic trip means, in which at least a portion of the energizing winding of the electromagnetic trip means serves as the heater for the thermally responsive trip element.

Another object of the invention is the provision of a circuit breaker with an improved electromagnetic trip means, the magnetic frame and armature of which are constructed of sheet metal and formed to the desired shape.

Another object of the invention is the provision of a circuit breaker with an enclosed trip device embodying a thermal trip element the trip characteristic of which is set during the assembly and calibration of the device, and an electromagnetic trip means the trip characteristic of which is adjustable within predetermined limits from outside the enclosure.

Another object of the invention is the provision of a circuit breaker trip device having an electromagnetic trip means, with an improved adjusting means for adjusting the trip characteristic of the trip means; the adjusting means including a movable member that is permanently set during the assembly and calibration of the breaker to provide a selected range of adjustment, and an operating member that is movable at will to adjust the trip characteristic within the pre-selected range.

Another object of the invention is the provision of an enclosed circuit breaker with a trip device mounted within the enclosure and an adjusting means that is operable from outside the circuit breaker enclosure to vary the trip characteristic of the trip device.

Another object of the invention is the provi-

sion of a circuit breaker embodying an improved trip device, as described above, that is simple, reliable in operation, and inexpensive to manufacture.

5 The novel features that are considered characteristic of the invention are set forth in particular in the appended claims. The invention itself, however, both as to structure and operation together with additional objects and advantages thereof will best be understood from the following detailed description of a preferred embodiment thereof when read in connection with the accompanying drawings in which,

15 Figure 1 is a plan view of a circuit breaker provided with the trip device of the present invention; a portion of the breaker enclosure cover having been cut away and the cover of the trip device removed to show certain structural features of the breaker and trip device.

20 Fig. 2 is a vertical sectional view of the circuit breaker shown in Fig. 1.

Fig. 3 is an enlarged plan view of the trip device, a portion of the cover being cut away to show certain structural details of the device.

25 Fig. 4 is a vertical sectional view of the trip device taken substantially on the line IV—IV of Fig. 3.

Fig. 5 is a fragmentary end elevational view of the circuit breaker illustrating the operating 30 member of one of the adjusting means of the trip device.

Fig. 6 is an enlarged plan view of the magnet frame and armature of one of the electromagnetic trip means of the trip device.

35 Fig. 7 is a view of the electromagnetic trip means shown in Fig. 6 and taken at right angles thereto.

Fig. 8 is a front elevational view of the adjusting means for one of the electromagnetic trip 40 means.

Fig. 9 is a side elevational view of the adjusting means shown in Fig. 8.

Fig. 10 is a view of the magnetic stamping before being formed into the magnet frame, and

45 Fig. 11 is a fragmentary sectional view of a portion of the trip device showing the manner in which the electromagnetic trip means is secured to the base of the trip device.

Referring to the drawings, and particularly Figs. 1 and 2 thereof, the circuit breaker illustrated is of the three-pole type and comprises in general a base 1, of a molded insulating material having a cover 3 also of molded insulating material, removably mounted thereon, a plurality of stationary contacts 5 and a plurality of movable

switch members 7 carrying movable contacts 9 which cooperate with the stationary contacts 5 to form the poles of the breaker, a common operating mechanism indicated generally at 11 for the switch members, and a unitary trip device indicated generally at 13.

The base 1 has a plurality of end terminals 15 and 17 mounted thereon adjacent each end by means of terminal screws 19 which engage threaded terminal inserts 21 imbedded in the base. The poles of the breaker are insulated from each other by insulating barriers 22 formed integral with the base 1, which align with similar barriers 23 formed integral with the cover 3.

Each stationary contact member 5 (only one being shown) is mounted on the inner end of a strip 25 of conducting material which is secured to the base 1 by means of a screw 27 and connected at its other end to the corresponding end terminal 15 by the terminal screw 19.

Each movable switch member 7 comprises a channel-shaped steel frame to the outer end of which is pivoted a contact carrying arm 29. The arm 29 has a stop 31 which engages the frame of the switch member 7 to limit counter-clockwise rotation of the arm 29 relative to the switch member 7. The movable contact 9 is secured to the outer end of the contact arm 29 for movement into and out of engagement with the co-operating stationary contact 5. The contact carrying arm 29 is provided with a tail piece 33 which is adapted to engage a spring pressed plunger 35 carried by the base 1, when the switch member is in closed circuit position. The spring pressed plunger 35 serves to provide a definite contact pressure between the movable contact 9 and the stationary contact 5 when the breaker is in closed circuit position.

All three of the switch members 7 have square openings provided therein adjacent their rear ends. An insulating tie bar 37 which extends across all three poles of the breaker engages the three square openings in the switch members 7 to mechanically connect the switch members for simultaneous movement by the common operating mechanism 11. The center pole switch member 7 is pivotally mounted on a U-shaped frame 39 by means of a pivot pin 41 which extends transversely between the side walls of the frame 39. The pin 41 serves to provide a common pivot axis for the assembly of switch members 7, all of which are mechanically tied together by the insulating tie bar 37.

The movable contacts 9 carried by the switch member 7 are electrically connected by means of flexible shunt conductors 43 to a plurality of U-shaped terminal members 45 (Fig. 1) mounted on the base by means of terminal screws 47 which engage threaded inserts 49 (Fig. 2) imbedded in the base 1. The terminal members 45 are adapted to be removably electrically connected to the corresponding terminals of the trip device 13 by means of the terminal screws 47.

The electrical circuits for each of the poles of the breaker are substantially the same. Beginning with the terminal 15, the current passes successively through the conducting strip 25, stationary contact 5, movable contact 9, and its associated conducting shunts 43, through the unitary trip device 13, and thence to the other end terminal 17.

An arc extinguishing means indicated at 51 is provided for each pair of the contacts of the breaker. The arc extinguishing means 51 may be of any suitable type, but is preferably of the

spaced plate type in which a plurality of slotted magnetic plates 52, each insulated from the other, is provided. Each arc extinguishing means 51 is disposed adjacent the arc path of its corresponding pair of contacts and is operable upon the establishment of an arc to move the arc into the spaces between the plates 52 where it is immediately cooled and extinguished in a well known manner.

10 The cover 3 of the circuit breaker is provided with a plurality of screened openings 53 which form an exit for the escape of hot gases which may be formed during circuit interruption. The cover 3 is also provided with a baffle 55 for directing the arc gases through the screened openings 53 and for preventing these gases from escaping through the opening provided in the cover for the operating handle.

15 The operating mechanism 11 of the circuit breaker is carried by the U-shaped frame 39 which is secured to the base by means of a plurality of screws 57. The mechanism comprises in general, the U-shaped operating member 58 pivoted on the sides of the frame 39 by means of pivot pins 59, a releasable cradle 61 which is pivoted on the frame 39 by means of a pivot pin 63, a pair of toggle links 65 and 67 and a pair of over-center springs 69 (only one being shown). The toggle link 67 is pivotally connected at its lower end by means of a pivot pin 71 to the central switch member 7 and has its upper end pivotally connected to the lower end of the toggle link 65 by knee pivot pin 73. The upper end of the toggle link 65 is pivotally connected to releasable carrier 61 by means of a pivot pin 75. The over-center springs 69 have their upper ends connected to the bight portion of the U-shaped operating member 58 and their lower ends pivotally connected to the knee pivot pin 73 which connects the links 65 and 67. The operating member 58 has an operating handle 77 of molded insulating material secured to the upper end thereof. The handle 77 has an operating knob 79 which extends through an elongated opening 81 provided 20 therefor in the cover 3, and with an arcuate shield portion 83 which serves to close the opening 81 in all positions of the operating member.

25 The carrier 61 is always biased in a clockwise direction about its pivot pin 63 by a component 50 of the force exerted by the over-center springs 69. The free end of the carrier 61 has a latch nose 85 which is normally engaged by a latch of the trip device 13 to hold the carrier 61 in a normal position, as shown in Fig. 2.

30 The trip device 13 is a unitary structure entirely assembled on its own base 87 which is of molded insulating material. A cover 89 of insulating material is mounted on the base 87 and cooperates therewith to form an enclosure for the trip mechanism assembled on the base 87. The trip device is removably mounted on the base 1 of the circuit breaker, in a suitable recess provided therefor adjacent one end of the base 1, by means of a pair of elongated screws 91 (Fig. 3) which 35 pass through the cover 89 and base 87 and engage in threaded inserts (not shown) embedded in the base 1 of the circuit breaker. The trip structure 13 includes a thermally responsive trip element 93 and an electromagnetic trip means indicated generally at 95 for each of the three poles of the breaker.

35 Each of the thermally responsive trip elements 93 is composed of suitable bimetallic material and has its lower end riveted to the angularly bent end of a conducting strip 97, so as to be disposed

in a vertical position. Each strip 87 is secured to the under side of the forward end of the base 87 by a transverse terminal plate 99 which is rigidly clamped to the base 87 by a pair of rivets 101 (Fig. 4). The forward end of the base 87 has three spaced recesses 103 (Fig. 3) which extend through the base to the terminal plates 99 for accommodating the intermediate terminal members 45 of the circuit breaker. The three terminal plates 99 have openings for receiving the intermediate terminal screws 47 of the breaker which serve to clamp and electrically connect the terminal members 45 to the terminal plates 99 of the trip device.

The opposite terminals 105 of the trip device comprise three conducting strips which are secured to the base 87 by means of screws 107 which extend upwardly through openings in the bottom of the base 87 and engage the strips 105 to clamp them to the base 87. The strips 105 have offset portions 109 which are perforated to receive the end terminal screws 19 of the circuit breaker which serve to clamp and electrically connect the terminals 105 of the trip device to the end terminals 17 of the circuit breaker.

Each of the three magnetic trip devices 95 comprises a U-shaped frame 111 which is cut from a plate of magnetic material and formed into the shape shown in Fig. 10. The plate is formed to a U shape by bending the leg portions 113 at right angles to the bight portion 115 and then the flaps 117 of the legs 113 are bent at right angles inwardly along the dotted lines 119 (Fig. 10) to provide parallel inwardly directed flanges 120 (Figs. 6 and 7). A U-shaped magnet 121 formed from a strip of magnetic material is nested within the U-shaped frame 111 and secured thereto by a center core member 123 which has a reduced portion 125 which extends through openings provided therefor in the bight portions of the frame 111 and magnet 121. The end of the reduced portion 125 of the core member 123 is spun over against the back of the U-shaped frame 111 and thus serves to clamp the U-shaped magnet 121 to the frame 111 and to retain the core member 123 in mounted position. One of the legs 113 of the magnet frame 111 has a pair of projecting ears 126 which are provided with aligned openings for receiving a pivot pin 127 for pivotally mounting an armature 129 to a leg of the magnet frame 111. The armature 129 consists of two strips 131 of magnetic material secured together face to face, and the strips 131 have opposed bump shaped bends 133 formed therein adjacent one end of the armature to provide a transverse opening for receiving the pivot pin 127. The armature 129 is thus pivotally mounted on one leg 113 of the magnet frame 111 for swinging movement into engagement with the end of the other leg 113 of the frame by means of the pin 127 which extends through the aligned openings of the ears 126 and through the transverse opening of the armature 129. The armature is biased away from the core 123 by means of a coil spring 135, the ends of which seat in wells 137 and 139 provided therefor in the core member 123 and armature 129 respectively.

The three assembled magnetic trip means 95 are mounted in spaced relation on the base 87 in recesses provided therefor, and each electromagnetic trip means is clamped in mounted position on the base 87 by means of a plurality of rivets 141 which pass through openings provided in the inturned flanges 120 of the legs 113 of magnet frame 111 as shown in Fig. 11.

Each of the electromagnetic trip means 95 is provided with an energizing winding 143 which consists of a curved copper strip 145 riveted to the angularly bent inner end of the conducting strip 105 and which encircles the core 123 of the electromagnetic trip means 95, and a second curved strip 147 composed of a suitable high electrical resistance material such as nickel or nickel alloy. The strip 147 is riveted at one end to the end of the copper strip 145 and also encircles the core member 123. The opposite end of the strip 147 is secured to the conducting strip 97 by means of the rivet which connects the bimetal trip element 93 to the strip 97. The two strips 145 and 147 are of such shape that they form a substantially helical winding encircling the core member 123, which is connected in series circuit with a corresponding pair of the contacts of the breaker. The high resistance strip 147 has a portion disposed in contact with a portion of the corresponding bimetal trip element 93 so that the strip 147 in addition to forming part of the energizing winding for the electromagnetic trip means 95 also serves as the heater for the bimetal trip element 93.

A common trip bar 149 of molded insulating material extends transversely across the three poles of the trip device 13 and is actuatable by any one of the three bimetallic trip elements 93, and also by any one of the three electromagnetic trip means 95. The trip bar is pivotally mounted on a pair of brackets 151 (Fig. 3) and is biased in a clockwise direction by means of a coil spring 153 which is connected between the trip bar and a bracket on the base 87. The trip bar 149 has three spaced downwardly extending projections 155, the lower ends of which are disposed in the path of movement of the armature 129, so as to be engaged and moved by the armatures when the armatures are moved to attracted position. The trip bar 149 is also provided with three spaced upwardly extending projections 157 which carry adjusting screws 159 at their upper offset ends adapted to be engaged by the upper free ends of the bimetallic trip elements 93. It will thus be seen that the trip bar 149 is adapted to be partially rotated in a counter-clockwise direction from its normal position shown in Fig. 4 to a tripping position by any one of the three bimetallic trip elements 93 in response to moderate and lower magnitude overloads of predetermined duration, and the trip bar is also partially rotatable in a counter-clockwise direction from its normal position to its tripping position by any one of the electromagnetic trip means 95 in response to heavy overloads and short circuit conditions.

The trip device is provided with a latch member 161 which normally engages and restrains the carrier 61 to maintain the toggle links in operative position for operation by the operating member of the breaker. The latch member 161 is slidably pivoted on a pivot pin 163 which is carried transversely between the legs 165 of a yoke-shaped bracket 167. The bracket 167 is secured to the base by means of the rivets 101 which retain the central pole terminal plate 99 to the trip base 87. The latch member 161 has a rearwardly extending notched projection 169 which is normally engaged by a projection 171 secured to the trip bar 149. The latch member 161 has two slots 173 for slidably engaging the pivot pin 163. A spring 175 which is coiled about the pivot pin 163 exerts a force which biases the latch member 161 in a clockwise direction about

the pivot pin 163 and also biases the latch member in the direction of the operating mechanism 11 as far as permitted by the slots 173. The movement of the latch member 161 in a clockwise direction under the influence of the spring 175 is limited by the engagement of the yoke portion of the latch member 161 with the yoke portion of the bracket 167 as best shown in Fig. 4. When the releasable carrier 61 of the circuit breaker is restrained in its normal position, that is, when the latch nose 85 thereof is engaged under the latch projection 171 of the latch member 161, the latch member is biased in counter-clockwise direction due to the relatively large force transmitted thereto by the carrier 61. This force is balanced by the trip bar 149 which, through its projecting portion 171, releasably engages the notched end of the projection 169 of the latch member 161 and prevents the latch member from turning under the biasing action of the carrier 61. When the trip bar 149 is moved in a counter-clockwise direction to its tripped position, it effects release of the latch member 161 which in turn releases the carrier 61 of the circuit breaker to effect a tripping operation as will be hereinafter described.

The yoke shaped bracket 167 has a pair of projecting legs 168 provided with notches 170 which engage projections 172 extending from the side walls of the frame 38 so as to accurately position the trip device 13 with respect to the breaker mechanism 11.

Each of the three electromagnetic trip means 95 is provided with an individual adjusting means indicated generally at 178 which serves to adjust the trip characteristic of the trip means. Each of the adjusting means 178 (Figs. 8 and 9) includes an angular bracket 181 which has its horizontal leg clamped against the base 87 of the trip device by means of the rivets 141 which secure the magnet assembly of the electromagnetic tripping means 95 to the base 87, as shown in Fig. 11. The bracket 181 is insulated from the conducting strip 105 by means of an insulating plate 183. The vertical leg 185 of the bracket 181 extends across an opening provided therefor in the end of the base 87 of the trip device, and is provided with an arcuate slot 187 and with a keyhole 189. A warped spring washer 191 is disposed against the inner surface of the leg 185 of the bracket 181, and this washer is provided with a keyhole slot 192 which cooperates with the keyhole slot 189 in the vertical leg 185 of the bracket 181 to mount a calibrating screw 193. The screw 193 has a reduced portion 195 and a threaded portion 197. The screw 193 is mounted by placing the washer 191 against the leg 185 of the bracket 181 with the keyhole slots 192 and 189 in alignment, the screw 193 being inserted through the enlarged portions of the keyhole slots and the reduced portion of the screw slipped into the reduced portion of the slots. The spring washer 191 is then rotated 180°, as shown in Fig. 8, to retain the calibrating screw 193 in mounted position. The enlarged threaded portion 197 and the head of the screw serve to retain the spring washer in tension with its edges against the vertical leg 185 of the bracket 181.

An angle shaped operating lever 199 has a threaded hub portion 201 which is threadedly mounted on the threaded portion 197 of the calibrating screw 193 (Fig. 9). The operating lever 199 has an offset portion 203 which extends through an opening provided therefor in the spring disk 191 and through the arcuate open-

ing 187 of the bracket 181. The lever 199 is also provided with an angular projection 205 which is normally engaged by the armature 129 of the electromagnetic tripping means 95, as shown in Fig. 4. The rotatable adjusting movement of the lever 199 is limited by the arcuate slot 187 of the bracket 181.

During the assembly and calibration of the breaker, each of the electromagnetic trip means 95 is given a preliminary setting or calibration by turning the calibrating screw 193 to obtain the correct maximum trip current setting or the correct range of adjustment of the electromagnetic trip means 95. When the electromagnetic trip means has been correctly calibrated by means of the adjusting screw 193, the operating lever 199 is soldered to the threads of the calibrating screw 193 to make the preliminary adjustment permanent. After the three electromagnetic tripping means 95 have been calibrated, as described above, the trip characteristic of each can be varied over a selected range by rotating the operating lever 199.

The rotation of the operating lever in a counter-clockwise direction, as viewed in Fig. 4, serves to increase the air gap between the armature 129 and the core 123, so that a larger amount of current is required to cause movement of the armature 129 to attracted position to effect the tripping operation of the device. Conversely rotation of the operating lever 199 in a clockwise direction serves to move the armature 129 closer to the core 123, reducing the air gap so that the electromagnetic trip means 95 will be operated in response to a lower current value. Thus the trip characteristic of each of the electromagnetic means 95 may be individually adjusted through a selected range by means of the adjusting means 178. The spring washer 191 of each of the adjusting means 178 is provided with a projection 207 (Figs. 8 and 9) which engages arcuately arranged serrations 209 provided in the leg 185 of the bracket 181. The projections 207 and the serrations 209 provide a notching means for releasably retaining the operating lever 199 in any adjusted position to which it is set. Each of the three adjusting means 178 is provided with a shield 211 (Fig. 4) of insulating material which has a recess through which the offset operating projection 203 of the operating lever 199 projects. The vertical leg 185 of the bracket 181 is provided with a suitable calibration scale 213 and with indicia 215 for indicating the high and low adjustment of the operating lever 199, and the scale and indicia are visible from outside the enclosure of the trip device through the recess in the shield 211 as shown in Fig. 5. It will be noted from Figs. 2 and 5 of the drawings that the shields 211 cover the heads of the calibrating screws 193 so as to prevent access thereto from outside the circuit breaker enclosing casing 1-3. An additional deterrent to unauthorized change in the setting of the calibrating screws is provided by the fact that the operating levers 199 are soldered or otherwise sealed to the calibrating screws after calibration of the device, as described above.

The base 1 of the circuit breaker is provided with three rectangular openings 217 (Fig. 5) in the end wall thereof adjacent the trip device 13. The openings 217 permit access to be had to each of the adjusting means 178.

The trip characteristic of each of the bimetallic trip elements 93 is adjustable by means of the adjusting screw 193 and the trip charac-

teristic of each of the bimetallic trip elements 93 is set during the assembly and calibration of the breaker, and the setting thus given is preferably made permanent by soldering the lock nut 219 which is mounted on the adjusting screw 159.

The operation of the circuit breaker is briefly as follows: With the breaker in open position, as shown in Fig. 2, let it be assumed that it is desired to manually close the circuit breaker. The operating member 58 is moved by means of a handle 79 in a clockwise direction about its pivot axis from the open circuit position shown in Fig. 2 to the closed circuit position. This movement of the operating member 58 moves the line of action of the over-center springs 69 to the right. As soon as the line of action of the over-center springs 69 crosses the pivot pin 75 which connects the upper toggle link 65 to the carrier 61, the force exerted by the springs moves the toggle links from their collapsed position, as shown in Fig. 2, to a made or in toggle position, causing the three mechanically connected movable switch members 7 to move to closed circuit position with a snap action carrying the movable contacts 9 into engagement with the stationary contacts 5. To open the circuit breaker, the operating member 58 is moved in a counter-clockwise direction about its pivot axis 59 from the closed position to the open position shown in Fig. 2. This movement of the operating member 58 moves the line of action of the over-center springs to the left. As soon as the line of action of the over-center springs crosses the axis of the pivot pin 75, the force exerted by the springs moves the toggle links 65 and 67 to their collapsed position, causing movement of the mechanically connected switch member 7 to open circuit position with a snap action and carrying the movable contacts 9 to open circuit position, as shown in Fig. 2.

When the breaker is in closed circuit position and an overload occurs in the circuit through any one of the poles of the breaker, the heater portion of the energizing winding 143 of the affected pole is heated, and since the bimetallic element 93 is in intimate contact with the heater portion of the winding, this element is also heated. When the bimetallic trip element 93 has been heated a predetermined amount, it deflects in a direction away from the operating mechanism 11 and effects movement of the trip bar 149 to tripping position. Movement of the trip bar 149 to tripping position effects release of the latch member 161 which, in turn, releases the carrier 61 of the breaker operating mechanism. When the carrier 61 is released, it is rotated in a clockwise direction about its pivot pin 63 and causes collapse of the toggle links 65 and 67, thereby opening the contacts of the breaker. Similarly, in the event of a short circuit or a heavy load in a circuit controlled by any one of the poles, sufficient magnetomotive force is supplied by the energizing winding 143 of the affected pole to cause the corresponding armature 129 to be attracted to the core member 123. The movement of the armature 129 to attracted position causes movement of the trip 149 to its tripped position to effect release of the carrier 61 and opening of the breaker as previously described in connection with the thermal trip operation.

Before the circuit can be reclosed following a tripping operation, it is necessary to reset the operating mechanism. A projection 221 on the

operating member 58 is provided for this purpose. To reset the mechanism, the operating handle 77 is moved in a counterclockwise direction, during which movement, the projection 221 engages and moves the carrier 61 in a counterclockwise direction. As the operating handle 77 nears the limit of travel in an opening direction, the latch nose 85 of the carrier 61 engages the over-hanging projection 177 of the latch 161, and slides the latch member 161 in a rearward direction to allow the latch nose 85 to clear the projection 177. When the handle 77 is released, the carrier 61 is returned a short distance by the overcenter springs 69 to its normal latched position where it is held by the latch member 161, the latch member 161, having been returned to its latched position by the spring 175 and re-engaged by the projection 177 on the trip bar 149. The entire breaker mechanism is now in open and reset position and may be closed by movement of the operating handle 77 to closed position as has previously been described.

While the invention has been disclosed in accordance with the provisions of the patent statutes, it is to be understood that various changes in the structural details thereof may be made without departing from the spirit of the invention. It is desired, therefore, that the appended claims be given the broadest reasonable construction permissible in the light of the prior art.

I claim as my invention:

1. In a circuit breaker having relatively movable contacts, a trip device operable in response to predetermined conditions to cause opening of said contacts comprising a core member, a movable armature, an energizing winding encircling said core comprising a flat strip of conducting material making more than one turn about said core and disposed with its flat sides perpendicular to the axis of said core, and a thermally responsive trip element disposed in heat transferring relation to said winding between turns thereof to be heated thereby.
2. In a circuit breaker having relatively movable contacts and an actuating mechanism therefor, a trip device operable in response to predetermined conditions to effect opening of said contacts comprising a core member, a movable armature, a substantially helical energizing winding for said core member connected in circuit with said contacts comprising a flat strip of conducting material making at least one complete turn about said core and disposed with its flat sides perpendicular to the axis of said core, said winding strip having a portion of increased electrical resistance, and a thermally responsive trip element having a portion thermally conductively joined to the increased resistance portion of said winding strip to be heated thereby.
3. In a circuit breaker having relatively movable contacts and an actuating mechanism therefor, a trip device operable in response to predetermined conditions to effect opening of said contacts comprising a core member, an armature for said core member movable to an attracted position to effect operation of the trip device, an energizing winding for said core connected in circuit with said contacts comprising a flat strip of conducting material making at least one complete turn about said core and disposed with its flat sides perpendicular to the axis of said core, said winding having a portion of increased electrical resistance, and a bimetallic trip element having a portion thermally

conductively joined to the increased resistance portion of said winding strip to be heated thereby, said element being operable when heated a predetermined amount.

4. In a trip device for a circuit breaker, a core member, a movable armature for said core member, a multi-turn energizing winding encircling said core comprising a flat strip of conducting material making at least one complete turn about said core and wound with its flat sides perpendicular to the axis of said core, said winding having a portion of increased electrical resistance; and a thermally responsive trip element having a portion thermally conductively joined to the increased resistance portion of said winding to be heated thereby.

5. In a trip device for a circuit breaker, a core of magnetic material, a movable armature for said core, a pair of terminals for connecting said device in the circuit, an energizing winding for said core comprising a flat strip of conducting material making more than one turn about said core and wound with its flat sides perpendicular to the axis of said core, said winding being supported by and connected between said terminals, and a bimetallic trip element supported by one of said terminals and having a portion thermally conductively joined to a portion of said winding between turns thereof so as to be heated by said winding.

6. In a trip device for a circuit breaker, an electromagnetic trip means comprising a generally U shaped member having legs which are provided with integral flange portions projecting inwardly from the edges of said legs, said member being cut and formed from a plate of magnetic material, an armature pivotally mounted on one of the legs of said member adjacent the end thereof for swinging movement into engagement with the other leg, and an energizing winding for said member.

7. In a trip device for a circuit breaker, an electromagnetic trip means comprising a member cut from a strip of magnetic material and formed to provide a U-shaped frame, one of the legs of which has a pair of inwardly directed parallel ears, an armature formed of a pair of strips of magnetic material secured together face to face and having opposed humped bends formed therein adjacent their one end to provide a transverse opening for receiving a pivot pin, said armature being pivotally mounted on said one leg for swinging movement into engagement with the other leg by a pivot pin which extends through aligned openings provided therefor in said ears and through the transverse opening of said armature.

8. In a trip device for a circuit breaker, an electromagnetic trip means comprising a member cut from a plate of magnetic material and formed to provide a U shaped frame, the legs of which are U shaped in section, a U shaped magnet secured to said frame and nested within the same, a core of magnetic material mounted on the bright portion of said magnet intermediate the legs thereof, an armature pivotally mounted on one of the legs of said U shaped frame for swinging movement into engagement with the end of the other leg, and an energizing winding encircling said core.

9. In a circuit breaker having relatively movable contacts, a trip device operable to effect opening of said contacts in response to predetermined conditions comprising an electromagnetic trip means including a core and a movable

armature biased away from said core and movable to an attracted position to effect operation of said trip device, spring means for biasing said armature away from said core, adjusting means for varying the trip characteristic of said electromagnetic trip means comprising an operating member mounted for limited rotatable adjusting movement to vary the normal position of said armature, and movable means for shifting the position of the rotatable operating member relative to the core to select the range of adjustment of said adjustable means.

10. In a circuit breaker, an enclosing casing, relatively movable contacts in said casing, a trip device in said casing operable to effect opening of said contacts in response to predetermined conditions comprising an electromagnetic trip means including a core and a movable armature biased away from said core and movable to an attracted position to effect operation of said trip device, adjusting means for varying the trip characteristic of said electromagnetic trip means comprising a movable operating member normally engaged by said armature, and mounted for limited adjusting movement for varying the normal position of said armature, said operating member being accessible from outside said casing, and means movable to shift the movable operating member toward or away from said core to calibrate the device for the maximum current setting, said last-mentioned movable means being substantially inaccessible from outside said casing.

11. In a circuit breaker, an enclosing casing, relatively movable contacts in said casing, a trip device in said casing operable to effect opening of said contacts in response to predetermined conditions comprising an electromagnetic trip means including a core and a movable armature biased away from said core and movable to an attracted position to effect operation of said trip device, adjusting means for varying the trip characteristic of said electromagnetic trip means comprising a movable operating member normally engaged by said armature, and mounted for limited adjusting movement for varying the normal position of said armature, said operating member being accessible from outside said casing, and means movable to shift the movable operating member toward or away from said core to calibrate the device for the correct maximum current setting, and notching means for releasably retaining said operating member in any adjusted position to which it is moved, said movable calibrating means being inaccessible from outside said casing.

12. In a circuit breaker, an enclosing casing, relatively movable contacts in said casing, a trip device mounted in a second enclosing casing inside the breaker enclosing casing, said trip device being operable to effect opening of said contacts in response to predetermined conditions and comprising an electromagnetic trip means including a core and a movable armature biased away from said core and movable to an attracted position to effect operation of the trip device and a thermally responsive bimetal element heated in response to the current of the circuit and operable when heated a predetermined amount to effect operation of the trip device, said bimetal element being given a permanent setting during the assembly and calibration of the device; and adjusting means for adjusting the trip characteristic of said electromagnetic trip means comprising a movable operating

member normally engaged by said armature and mounted for limited adjusting movement to adjust the normal position of said armature relative to the core, said operating member being accessible from outside the circuit breaker enclosing casing, and means movable during the assembly and calibration of the breaker for shifting the position of the operating member relative to the core to calibrate the electromagnetic trip means, and means for substantially preventing unauthorized change in the setting of said movable calibrating means.

13. In a circuit breaker, an enclosing casing, relatively movable contacts in said casing, a trip device in said casing operable in response to predetermined conditions to cause opening of said contacts including a magnetically actuated trip element movable from a normal position to a tripping position to effect operation of the trip device and a thermally responsive bimetal element heated in response to the current of the circuit and operable when heated a predetermined amount to effect operation of the trip device, said bimetal element being given a permanent setting during the assembly and calibration 25

- of the device, adjusting means for adjusting the trip characteristic of said magnetically actuated trip element comprising an operating member normally engaged by said trip element and mounted for limited adjusting movement to adjust the normal position of said trip element and means movable to shift the position of said movable operating member to calibrate the device for the maximum current setting, said 10 operating member being accessible from outside said casing, and means for preventing unauthorized change in the setting of said movable means.
14. A circuit breaker trip device comprising an electromagnet energized by the current of the circuit, said electromagnet having a pivoted armature movable to an attracted position in response to said predetermined current conditions to cause automatic opening of the breaker; and a pivoted lever having an end engaging the 15 back of said armature and movable along the back of said armature toward and away from the pivot of said armature to adjust the normal position of said armature.
